COMBINED MASSAGER AND INFRA-RED HEAT LAMP

Wallace L. Minto, 525 River Vale Road, Westwood, N.J.

Filed May 12, 1959, Ser. No. 55,878

Term of patent 14 years

(Cl. D83—5)

Fig. 1 is a bottom plan view of a combined massager and infra-red heat lamp embodying my new design;

Fig. 2 is a side elevational view thereof, a portion of the lip being broken away to show the side and bottom configurations of the article;

Fig. 3 is a top plan view thereof; and

Fig. 4 is an end elevational view thereof.

I claim:

The ornamental design for a combined massager and infra-red heat lamp as shown.
